UNITED STATES PATENT OFFICE.

NORMAN O. JOHNSON, OF CHICAGO, ILLINOIS, ASSIGNOR, BY MESNE ASSIGNMENTS, TO
ILLINOIS CARTON & LABEL COMPANY, OF CHICAGO, ILLINOIS, A CORPORATION OF
ILLINOIS.

CARTON AND ITS BLANK.

Application filed July 14, 1928. Serial No. 292,803.

My invention pertains to cartons or containers and the blanks from which they are formed, one of the leading aims and purposes of the invention being to provide a 5 carton which can be economically manufactured, which will protect its contents effectually, and which does not require the use of adhesive in its production, the folding of the blank so interlocking the parts of the 10 structure as to prevent their unintentional unfolding.

To enable those skilled in this art to have a full and complete understanding of the invention, both from structural and functional standpoints, a present, desirable or preferred embodiment of the invention has been illustrated in the accompanying drawings, forming a part of this specification, and to which reference should be had in connection with the following detailed description, like reference characters designating the same parts throughout the several views of the drawings.

In these drawings:—

25 Figure 1 is a face view of the pasteboard blank from which the carton is formed;

Figure 2 is a perspective view showing the first folding operation of the blank;

30 Figure 3 is a similar, perspective view indicating a subsequent folding operation;

Figure 4 illustrates, in like manner, the succeeding step in the folding action; and

Figure 5 is a perspective view of the completed carton.

35 Referring to these drawings, and particularly initially to Figure 1 thereof, it will be perceived that the blank comprises a central, substantially-rectangular portion divided by parallel, folding lines or creases 11, 12, 13 and 14 into a complete or unbroken, outer front section 15, a next adjacent, similar, bottom section 16, a like, succeeding, outer, back section 17, a comparable, outer, top section 18, and an adjoining flap 19, two 40 corners of which are rounded at 21, 21, as shown, to facilitate its introduction into the space provided for it in the finished article.

45 The ends of the front section 15 have parallel, folding lines or creases 22, 22 beyond 50 which are two, inner, end-wall sections 23,

23 connected at their outer ends, along folding or crease lines 24, 24, to intermediate back sections 25 and 26, the combined lengths of which are substantially equal to the length of the companion or cooperating, 55 back section 17, although the part 25 is made purposely shorter than the part 26, so that the break or joint 20 between them will not be at the middle of the length of the finished receptacle. 60

At both ends of the bottom section 16 there are outer end-wall sections 27, 27 with folding or crease lines 28, 28 between them and the specified bottom portion.

Such parts 27 are separated from the sections 23, 23, 25 and 26 by reason of slits 29 which divide them, as shown.

Directly beyond each, such, outer, end portion 27, with a corresponding intervening crease or folding line 31, there is an inner, 70 top-wall section 32 which carries on one side an inner, back section 33 with an appropriate crease or folding line 34 between them, the parts 33, 33 being of equal length.

It is to be understood that this blank is 75 formed of a single, flat piece of pasteboard, cardboard, or equivalent foldable material of appropriate thickness and of the shape and supplied with the folding lines and the cuts or slits clearly illustrated and specified 80 in detail above.

The first step in the preferred, folding operation is to bend the blank along the lines or creases 11, 22 and 24, as shown in Figure 2, thus temporarily forming or providing an open-top receptacle having the bottom 85 16, the two ends 23, 23 and the front and back walls 15 and 25—26.

The body to be enclosed in the carton may now be placed in such open container, if desired, or the indicated folding operation may be performed around such body or article, for instance, a bottle, whereupon the folding operation continues by bending the blank along the lines 28, 28, whereby the 90 end-walls 27, 27 are positioned just outside of and bear against and reinforce the exterior faces of the inner end-walls 23, 23.

95 Then the folding continues by flexing the blank along the lines or creases 31 and 34, 100

(see Figure 3) which brings the portions 32, 32 over the previously open top of the receptacle and positions the inner back sections 33, 33 just inside of the intermediate, back sections 25 and 26. This condition of the structure is shown in Figure 4.

In view of the fact that the parts 33, 33 are then inside of the inner end-walls 23, 23, the sections 27, 27 are securely locked in place against the portions 23, 23.

Inasmuch as the parts 25 and 26 are of different lengths, whereas the portions 33, 33 are of the same length, the joints between the ends of such companion elements are not in register, thus giving the box or carton adequate strength to withstand the strains to which it may be subjected.

Thereupon, the blank is folded along the lines 12, 13 and 14, and the flap 19 is introduced or inserted between the front section 15 and the adjacent edges of the top wall portions 32, 32, whereby the flap is securely and firmly retained in place against accidental unfolding of the box.

In order that such flap may be readily inserted in the position indicated and without bulging or distorting any of the parts of the container, the original blank is desirably provided with substantial gaps or slots 35, 36 between the adjacent edges of the parts 32 and 25 and 32 and 26, so that the elements 32 are slightly narrower than the end wall portions 27 to which they are attached; hence providing a slight space for the easy introduction of the flap.

From the foregoing it should be clear that the completed or finished carton has a single-thickness bottom 16, a double thickness front-wall composed of the outer element 15 and the inner, adjacent flap 19, a triple-thickness back composed of the broken or divided, inner thickness formed by the parts 33, 33, the intermediate, divided thickness composed of the parts 25, 26, and the unbroken outer thickness provided by the blank section 17, a double-thickness top-wall made up of an inner, divided or broken thickness composed of the sections 32, 32 and an overlying, unbroken thickness formed by the section 18, and two end-walls, each of which is of double-thickness constituted by the inner section 23 and the associated outer section 27.

With but slight, or no, modification of the blank depicted, it may be folded somewhat differently to provide a carton with much the same characteristics as that already presented.

In such case, the blank is first folded along the lines 28, 31 and 34 and then folded along the lines 11, 22 and 24, whereupon the completion of the bending along the lines 12, 13 and 14 and the introduction of the flap into position is consummated.

Such a carton will have the same thickness of walls as the one already described, but the

portions 27, 27 will then comprise the inner end-walls and the part 23, 23 the companion, outer end-walls, the sections 33, 33, in that instance, forming the inner thickness of the triple back, while the parts 25 and 26 comprise the inner layer of such three-ply back.

Still a third manner of folding the blank comprises bending it on the lines 11, 22 and 24, then along the lines 28, 31 and 34 with the portions 33, 33 outside of, instead of inside of, the elements 25, 26 and completing the folding along the lines 12, 13 and 14 with the insertion of the flap.

Such a completed structure, while having certain advantages, does not lock the end-walls together so securely or effectively as is accomplished by the preferred folding action first detailed hereinbefore.

With a moderate degree of practice a person can fold this blank and introduce the article to be housed in the container with great rapidity and ease.

Those acquainted with this art will readily appreciate that the invention, as defined by the appended claims, is not necessarily limited or restricted to the precise and exact details of structure and modes of operation presented and that many, minor, mechanical changes may be incorporated without departure from the heart and essence of the invention and without the loss or sacrifice of any of its substantial or material benefits or advantages.

I claim:

1. A single-piece foldable blank for forming a carton having five, parallel, directly-adjacent sections with folding lines between them, the ends of the first of said sections having lengthwise extensions constituting end-wall sections, the latter having outer end extensions comprising back sections, the outer ends of the second of said parallel sections having extensions constituting end-wall sections, the outer ends of the latter having extensions forming top-wall sections, said top-wall sections having side projections forming back sections.

2. A carton formed of a single-piece folded blank and having a single-thickness single-piece bottom-wall, a double-thickness front-wall composed of a single-piece outer thickness, and an inner single-piece flap, a double-thickness top-wall composed of a divided inner thickness and a single-piece outer thickness, a triple-thickness back-wall formed of a divided inner thickness, a divided intermediate thickness, and a single-piece outer thickness, and opposite double-thickness end-walls each thickness of which is a single-piece element.

3. A carton formed of a single-piece folded blank and having a single-piece outer front, bottom, back, top and flap with said flap attached to said top and folded inside of said front, inner single-piece end-walls attached

directly to the ends of said front, an intermediate back composed of sections directly connected to the ends of said end-walls, outer single-piece end-walls directly connected to the ends of said bottom, an inner divided top formed by extensions directly connected to the ends of said outer end-walls, and a di-

vided inner back composed of extensions on the sides of the sections forming said inner top.

In witness whereof I have hereunto set my hand and seal.

NORMAN O. JOHNSON. [L.s.]
